UNITED STATES PATENT OFFICE.

ROBERT P. CALVERT, OF WILMINGTON, DELAWARE, ASSIGNOR TO E. I. DU PONT DE NEMOURS AND COMPANY, OF WILMINGTON, DELAWARE, A CORPORATION OF DELAWARE.

PROCESS OF SEPARATING NITRATES OF POTASSIUM AND SODIUM.

1,356,806.

Specification of Letters Patent. Patented Oct. 26, 1920.

No Drawing.

Application filed August 1, 1917. Serial No. 183,825.

To all whom it may concern:

Be it known that I, ROBERT P. CALVERT, of Wilmington, in the county of New Castle and in the State of Delaware, have invented a 5 certain new and useful Improvement in Processes of Separating Nitrates of Potassium and Sodium, and do hereby declare that the following is a full, clear, and exact description thereof.

10 My invention relates particularly to a process for obtaining potassium nitrate from mixtures of the same with sodium nitrate.

The object of my invention is to provide an advantageous process by means of which 15 potassium nitrate may be obtained from mixtures of the same with sodium nitrate which mixtures may contain other constituents. More particularly, the object of my invention is to provide a process by means 20 of which mixtures of potassium and sodium nitrates, and particularly such mixtures containing from 20 to 40% of potassium nitrate may be treated, so as to effectively separate the potassium nitrate from the sodium nitrate. A further object is to bring about 25 this separation without necessitating the decomposition of the constituents. A further object is to bring about the separation of potassium and sodium nitrates by treating 30 the same at a low temperature, at which said nitrates have different degrees of solubility in water. A further object is to make use of the mother liquor produced in the process so as to separate the constituents therein 35 and thus bring about the use of a continuous process while, at the same time, avoiding waste of the materials treated. Further objects of my invention will appear from the detailed description thereof contained here- 40 inafters.

While my invention is capable of being carried out in many different ways, for the purpose of illustration I shall describe only certain modes of procedure by means of 45 which my invention may be conducted. For example, I may proceed as follows:

A mixture containing from 20 to 40% potassium nitrate and 55 to 75% sodium nitrate, and which may contain also other 50 constituents as, for example, small proportions of boric acid, calcium sulfate, potassium perchlorate, sodium chlorid, magnesium chlorid, insoluble materials, etc., is treated with a quantity of water sufficient to dissolve substantially all of the sodium nitrate and, for example, for this purpose, I 55 may add 100 parts of such mixture of nitrates to 80 parts of water. Thereafter refrigeration is applied, which may be by means of the application of ice, cold brine, 60 ammonia, etc. Any desired lower temperatures may thus be obtained, but by way of example, I may lower the temperature in this manner to 5° C., or preferably to -15° C. When the desired temperature has been 65 reached the liquid is separated from the crystals by gravity, pressure filtration, or centrifuging. The crystals thus obtained will contain from 40 to 100% potassium nitrate. In this way a product is obtained containing 70 a very high percentage of potassium nitrate. If desired, this may be subjected to repeated re-crystallization to increase the purity of the potassium nitrate. Furthermore, if desired, the boric acid may be removed by dissolving the potassium nitrate in water, adding lime, and filtering through a pressure filter. This is preferably done 75 before the first re-crystallization. Instead of applying water to the mixed nitrates, as 80 above indicated, the process may be carried out by treating mixed nitrates already dissolved in water in which case the refrigeration is applied to the solution either directly or after dilution with water to give the desired concentration. The amount of water present affects the percentage of the total 85 potassium nitrate obtained by the cooling. In the case where it is desired to treat a solution of mixed nitrates in which the percentage of sodium nitrate is larger than that 90 above referred to, it is desirable to decrease the proportion of the same before subjecting the solution to refrigeration. In treating such a solution I, therefore, first concentrate 95 the solution to a point where it is substantially saturated with sodium nitrate at the boiling point, and then cool it to the point at which the solution becomes substantially saturated with the potassium nitrate present. 100 When this is done crystals of sodium nitrate containing only a very small amount of potassium nitrate will separate out, and the remaining solution will ordinarily contain one part of potassium nitrate to three parts 105 of sodium nitrate. For example, if a solu-

tion containing five to six parts of sodium nitrate, and one part of potassium nitrate is to be treated, I evaporate the solution until it reaches the density of 54° Bé., whereupon 5 the solution is allowed to cool to 25° C. and the deposited crystals of sodium nitrate are then removed. The mother liquor is then subjected to the refrigeration as above described.

10 After the refrigeration has been carried out, according to the above methods, the mother liquor will contain sodium nitrate and potassium nitrate in the proportions of 5.7 to 1. This mother liquor may, therefore, 15 be concentrated to a density of 54° Bé. and then allowed to cool to 25° C., in the same way that the high sodium nitrate and low potassium nitrate solution, above referred to was treated, thus depositing crystals of sodium 20 nitrate and leaving a solution containing sodium nitrate and potassium nitrate in the proportions of approximately 3 to 1. Inasmuch as the mother liquor thus remaining contains potassium nitrate and sodium nitrate in substantially the same proportions 25 as the mixed nitrates or solution thereof initially treated by the process as above described, I may add this mother liquor to a quantity of the mixed nitrates solution as initially treated, and then subject the same 30 simultaneously to refrigeration to bring about a separation of the sodium nitrate from the potassium nitrate in the manner described above in detail. The mother liquor obtained from this separation may 35 be used over again in the same way. In this manner any loss of the substances present in the mother liquor is avoided, thus making the process a continuous one.

40 While I have described my invention above in detail, I wish it to be understood that many changes may be made therein without departing from the spirit thereof.

I claim:

- 45 1. The process which comprises separating potassium nitrate from a mixture of the same with sodium nitrate by utilizing the differences of solubility of the same at low temperatures, so as to separate crystals of potassium nitrate from the mother liquor containing the sodium nitrate in a larger percentage than the potassium nitrate.
- 50 2. The process which comprises separating potassium nitrate from a mixture of the same with sodium nitrate by utilizing the differences of solubility of the same at a temperature as low as 5° C., so as to separate crystals of potassium nitrate from the mother liquor containing sodium nitrate.
- 55 3. The process which comprises separating potassium nitrate from a mixture of the same with sodium nitrate by utilizing the differences of solubility of the same at low temperatures, so as to separate crystals of potassium nitrate from the mother liquor
- 60 65

containing the sodium nitrate in a larger percentage than the potassium nitrate, and then recrystallizing the potassium nitrate.

4. The process which comprises separating potassium nitrate from a mixture of the same with sodium nitrate by utilizing the differences of solubility of the same at a temperature as low as 5° C., so as to separate crystals of potassium nitrate from the mother liquor containing sodium nitrate, 70 and then recrystallizing the potassium nitrate.

5. The process which comprises separating potassium nitrate from a mixture of the same with sodium nitrate in which the potassium nitrate is at least 20% of the mixture of nitrates present, by utilizing the differences of solubility of the same at low temperatures, so as to separate crystals of potassium nitrate from the mother liquor 80 containing the sodium nitrate in a larger percentage than the potassium nitrate.

6. The process which comprises separating potassium nitrate from a mixture of the same with sodium nitrate in which the potassium nitrate is at least 20% of the mixture of nitrates present, by utilizing the differences of solubility of the same at a temperature as low as 5° C., so as to separate crystals of potassium nitrate from the 90 mother liquor containing sodium nitrate.

7. The process which comprises separating potassium nitrate from a mixture of the same with sodium nitrate in which the potassium nitrate is at least 20% of the mixture of nitrates present, by utilizing the differences of solubility of the same at low temperatures, so as to separate crystals of potassium nitrate from the mother liquor containing the sodium nitrate in a larger 100 percentage than the potassium nitrate, and then recrystallizing the potassium nitrate.

8. The process which comprises separating potassium nitrate from a mixture of the same with sodium nitrate in which the potassium nitrate is at least 20% of the mixture of nitrates present, by utilizing the differences of solubility of the same at a temperature as low as 5° C., so as to separate crystals of potassium nitrate from the 110 mother liquor containing sodium nitrate, and then recrystallizing the potassium nitrate.

9. The process which comprises separating potassium nitrate from a mixture of the same with sodium nitrate in which the potassium nitrate is at least 20% of the mixture of nitrates present, by utilizing the differences of solubility of the same at low temperatures, so as to separate crystals of potassium nitrate from the mother liquor containing sodium nitrate, then concentrating the mother liquor, cooling the same so as to remove the sodium nitrate to obtain a mother liquor containing a higher percent- 115 120 125 130

age of potassium nitrate; then adding thereto a fresh quantity of mixed nitrates of substantially the above mentioned proportions and cooling the same in a similar manner to separate potassium nitrate crystals from the remaining mother liquor.

10. The process which comprises separating potassium nitrate from a mixture of the same with sodium nitrate in which the potassium nitrate is at least 20% of the mixture of nitrates present, by utilizing the differences of solubility of the same at a temperature as low as 5° C., so as to separate crystals of potassium nitrate from the mother liquor containing sodium nitrate, then concentrating the mother liquor, cooling the same so as to remove the sodium nitrate to obtain a mother liquor containing a higher percentage of potassium nitrate, then adding thereto a fresh quantity of mixed nitrates of substantially the above mentioned proportions and cooling the same in a similar manner to separate potassium nitrate crystals from the remaining mother liquor.

11. The process which comprises separating potassium nitrate from a mixture of the same with sodium nitrate in which the potassium nitrate is at least 20% of the mixture of nitrates present, by utilizing the differences in solubility of the same at temperatures as low as 5° C., so as to separate crystals of potassium nitrate from the mother liquor containing sodium nitrate, then concentrating the mother liquor and allowing the same to cool to an intermediate

temperature so as to separate out the sodium nitrate therefrom by cooling.

12. The process which comprises separating potassium nitrate from a mixture of the same with sodium nitrate in which the potassium nitrate is at least 20% of the mixture of nitrates present, by utilizing the differences of solubility of the same at temperatures as low as 5° C., so as to separate crystals of potassium nitrate from the mother liquor containing sodium nitrate, then concentrating the mother liquor and allowing the same to cool so as to separate out the sodium nitrate therefrom by cooling to an intermediate temperature, and then depositing potassium nitrate therefrom by again cooling to the lower temperature mentioned.

13. The process which comprises concentrating a solution of mixed alkaline nitrates containing sodium nitrate together with less than 20% of potassium nitrate, cooling sufficiently to crystallize out so much of the sodium nitrate as to leave a liquor containing above 20% of the nitrate content in the form of potassium nitrate, separating the sodium nitrate so crystallized, and then cooling the residual liquor to a temperature so low as to crystallize out comparatively pure potassium nitrate.

In testimony that I claim the foregoing I have hereunto set my hand.

ROBERT P. CALVERT.
